UNITED STATES PATENT OFFICE.

MARTIN HAUSER, OF KANSAS CITY, MISSOURI.

VENTILATOR.

1,319,526.

Specification of Letters Patent. Patented Oct. 21, 1919.

Application filed March 14, 1919. Serial No. 282,669.

To all whom it may concern:

Be it known that I, MARTIN HAUSER, a citizen of the United States, residing at Kansas City, in the county of Jackson and State of Missouri, have invented certain new and useful Improvements in Ventilators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to ventilators and it is particularly adapted for use in connection with school rooms, auditoriums, theaters, lecture halls and the like where individual ventilators are distributed over a relatively large area. One of the objects of the invention is to provide an inexpensive, durable and efficient ventilator which may be conveniently attached to a floor or similar support and should the occasion demand, provide a base or support for an article of furniture, such as a seat, desk, table or the like.

In the drawings, Figure I is a sectional view through a ventilator constructed in accordance with my invention.

Fig. II is a detail perspective view of the same.

Fig. III is a fragmentary sectional view through the shell, part of the damper being shown in elevation.

Fig. IV is a side elevational view of a modified form of device used as a chair support, and

Fig. V is a sectional view of the chair support.

Referring now to the drawings by numerals of reference:

1 designates a hot air flue shown as extending through the floor 2 of a suitable building. Capping the flue is a concavo-convex shell 3 having a closed upper end wall 4 and a peripheral flange 5, the latter being adapted to receive the fastening devices 6 whereby the shell may be secured to the floor. The peripheral wall of the shell is provided with elongated vertical slots 7 as best shown in Figs. I and II, whereby the air discharging from the flue 1 may pass through the openings or slots

7 into the surrounding atmosphere to heat or ventilate the building, as the case may be.

8 and 9 are inwardly projecting guide ribs which engage notches 10 and 11 in the peripheral flange 12 of the vertically adjustable damper 13, which is shown as consisting of a truncated cone-shaped disk, adjustably connected to an adjusting screw 14 suspended from the end 4 of the shell 3. The damper 13 is adapted to entirely close over the end of the conduit 1 but through the medium of the adjusting screw is adapted to move vertically away therefrom to permit discharge of the air from the flue 7 through the openings 7, the position of the damper determining the effective cross sectional area of the slots or openings 7 because the outer diameter of the damper is slightly less than the inner diameter of the shell.

In Figs. IV and V, I have shown a slightly modified form of ventilator in which the concavo-convex shell 15 is provided with a boss or enlargement 15' to receive a tiltable socket member 16 on which is mounted a standard 17 carrying a seat 18. The damper 19 is secured to a bolt 20 which is exteriorly accessible whereby the damper may be raised and lowered toward and away from the flue 1. Within the boss 15' is a recess 21 receiving a nut 22 on the hollow bolt or sleeve 23, the head 24 of which bears upon the seat 25 of the standard 17. The openings in the boss 15' and in the socket member 16 through which the sleeve 23 passes are slightly larger than the exterior of the sleeve so that the sleeve can be tilted and consequently permit tilting of the socket member 16 so that the seat 18 may be tilted to the proper angle. The construction just described enables the device to be so arranged that it serves the dual purpose of both a ventilator and a furniture support although obviously slightly more expensive than the construction shown in Figs. I, II and III.

From the foregoing it will be seen that the ventilator will be inexpensive but efficient, the cost being greatly reduced because it will consist of substantially two castings, the outer shell and the damper, which may be readily cast and secured together by a commercial screw or bolt 14, the damper acting as a nut as well as the adjusting member (see Fig. I), and it will be appreciated that the cost of such a device is an important

factor when it is considered that in some auditoriums the number of ventilators used may run into the thousands.

Having thus described my invention, what I claim as new therein, and desire to secure by Letters Patent, is:

1. In a ventilator, the combination with a flue, of an inverted concavo-convex shell surrounding the flue and having vertically arranged elongated slots in the wall thereof, a screw suspended from the center of the shell, and a damper threaded on the screw and vertically adjustable with relation to the flue and to the elongated slots upon turning 15 of the screw.
2. In a ventilator, the combination with a flue, of an inverted concavo-convex shell surrounding the flue and having vertically arranged elongated slots in the wall thereof, 20 a screw suspended from the center of the shell, and a conical damper threaded on the screw and vertically adjustable with relation to the flue and to the elongated slots upon turning of the screw.
- 25 3. In a ventilator, the combination with a flue, of an inverted concavo-convex shell surrounding the flue and having vertically arranged elongated slots in the wall thereof, a screw suspended from the center of the shell,

and a damper threaded on the screw and 30 vertically adjustable with relation to the flue and to the elongated slots upon turning of the screw, the screw having a head projecting through the horizontal wall of the shell whereby access thereto may be had for 35 operation by a tool.

4. A ventilator comprising a cap-shaped shell consisting of a concavo-convex body having vertically elongated slots in the side wall thereof, a screw introduced from the 40 exterior through the shell and located in the center thereof, and a damper threaded to and suspended by the screw, said damper being vertically adjustable with respect to the elongated slots.

45 5. A ventilator comprising an inverted concavo-convex shell having elongated slots in the wall thereof, a boss carried by the horizontal portion of the shell and provided with a central opening, a furniture standard 50 adapted to be seated upon the boss having an opening alining therewith, a screw projecting through the standard and the boss and having a threaded portion at its lower end, and a vertically adjustable damper carried by the threaded end of the screw.

In testimony whereof I affix my signature,
MARTIN HAUSER.
